(57) **CLAIM**

The ornamental design for a die, as shown and described.

DESCRIPTION

FIG. 1 is a plan view of a die in which a first face is shown, upwardly-oriented so as to show the ornamentation thereon, while all other faces are left blank for clarity;

FIG. 2 is a plan view of a die in which a second face is shown, upwardly-oriented so as to show the ornamentation thereon, while all other faces are left blank for clarity;

FIG. 3 is a plan view of a die in which a third face is shown, upwardly-oriented so as to show the ornamentation thereon, while all other faces are left blank for clarity;

FIG. 4 is a plan view of a die in which a fourth face is shown, upwardly-oriented so as to show the ornamentation thereon, while all other faces are left blank for clarity;

FIG. 5 is a plan view of a die in which a fifth face is shown, upwardly-oriented so as to show the ornamentation thereon, while all other faces are left blank for clarity;

FIG. 6 is a plan view of a die in which a sixth face is shown, upwardly-oriented so as to show the ornamentation thereon, while all other faces are left blank for clarity;

FIG. 7 is a plan view of a die in which a seventh face is shown, upwardly-oriented so as to show the ornamentation thereon, while all other faces are left blank for clarity;

FIG. 8 is a plan view of a die in which an eighth face is shown, upwardly-oriented so as to show the ornamentation thereon, while all other faces are left blank for clarity;

FIG. 9 is a plan view of a die in which a ninth face is shown, upwardly-oriented so as to show the ornamentation thereon, while all other faces are left blank for clarity;

FIG. 10 is a plan view of a die in which a tenth face is shown, upwardly-oriented so as to show the ornamentation thereon, while all other faces are left blank for clarity;

FIG. 11 is a first isometric view of a die with all faces left blank for clarity; and,

FIG. 12 is a second isometric view of a die with all faces left blank for clarity.
